RECORD FILING DEVICE

Marchand B. Hall and Sylvan K. Ketterman, Chicago, Ill., assignors to Acme Visible Records, Inc., Chicago, Ill., a corporation of Delaware

Application August 28, 1944, Serial No. 551,491

7 Claims. (Cl. 129—16)

1

This invention relates to improvements in visible record filing devices, and particularly to a cabinet for vertically supporting accounting and the like loose leaf record cards of the class wherein in the cabinet is wider than the individual cards and the cards are provided with notches opening to their lower edges and thereby engageable with spaced bars extending longitudinally of the cabinet base so as to permit the cards to be filed and positioned in the form of a series or group of overlapping cards or in laterally offset echelons, and to separators or dividers for the card echelons.

It is a particular object of the present invention to provide an improved main divider or separator for record filing devices of the foregoing class adapted for resilient cooperative engagement with the filing cabinet whereby the said divider may be quickly and with ease interlockingly engaged with or disengaged from the cabinet, but which remains in firm pivotal engagement therewith in operative use so as to inhibit tendency of the loose leaf record cards from riding upwardly and becoming displaced.

Further objects relate to other details of the main divider construction, the cabinet construction, sub-dividers, and an improved capacity adjustment member, together with the advantages and economies thereof which will be apparent from a consideration of the following specification and drawings, wherein:

Fig. 1 is a side elevational view of a loose leaf record card filing cabinet, embodying our invention, with parts broken away and parts in section.

Fig. 2 is a relatively enlarged, fragmentary transverse sectional view of the cabinet of Fig. 1 illustrating in detail the cooperative engagement means between a card separator and the cabinet, in accordance with our invention.

Fig. 3 is a section on the line 3—3 of Fig. 2.

Fig. 4 is a section on the line 4—4 of Fig. 2.

Fig. 5 is a transverse section on the line 5—5 of Fig. 1 illustrating a main divider panel and its cooperative relationship with the cabinet.

Fig. 6 is a transverse section on the line 6—6 of Fig. 1 illustrating the end capacity adjustment panel and its cooperative relationship with the cabinet.

Fig. 7 is a transverse section on the line 7—7 of Fig. 1 illustrating a sub-divider panel in cooperative relationship with the cabinet.

2

Referring to the drawings, Fig. 1 illustrates a loose leaf record filing cabinet comprising a pair of parallel side walls 10 and a pair of inclined end walls 11, the end walls 11 converging towards each other adjacent the base of the cabinet, the cabinet being mounted on suitable supporting legs or standards such as 12. By reason of the inclined end walls, the operator or user of the filing cabinet may be conveniently seated facing one end thereof, the inclined end wall providing knee access to enable the body of the operator to be brought relatively close to the cabinet and to facilitate use thereof in a seated position. The cabinet is further provided with a bottom 13, the bottom being secured between the side walls 10 and recessed within the end walls 11 in suitable transverse notches, such as notches 14 or 15, placed at various levels and whereby the base of the cabinet 13 may be elevated or lowered to suit the height of the record cards and dividers to be employed therewith.

The base of the cabinet 13 is provided with a plurality of equally spaced longitudinally extending bars 16 seated into and projecting from the surface thereof, the bars 16 being adapted to extend into the lower marginal edges of the loose leaf record cards 17 and to be embraced by the downwardly opening notched areas 18 thereof, to retain the cards against lateral movement, and in desired off-set or echelon formation. The base 13 may be further provided, between the spacer bars 16, with inserts 19 of tractive material such as corduroy or the like pile fabric to prevent undue or undesirable slippage of the cards 17 longitudinally of the cabinet.

As previously indicated the cabinet and the respective dividers therefor formed in accordance with the present invention, are adapted for supporting a specific but generally conventional form of loose leaf record card in a generally vertical position, and for this purpose the relationship of cards 17 and their notch areas 18 with the spacer bars 16, is conventional, so as to permit an echelon of cards to be extended transversely of the cabinet in edgewise overlapped relationship, the cards being maintained in laterally spaced overlapping relationship by means of the aforesaid card notches and cabinet spacer bars, the cards being generally overlapped as indicated by the dotted lines in Fig. 5. Cards of this class conventionally

employ a signal or marking which is normally covered or concealed by an adjacent card when an adjacent card is moved or drawn out of position.

It is also conventional in filing devices of the class described to employ relatively heavy or rigid elongated separator or divider panels since the width of the cabinet is much greater than the width of any individual card, and in operative use, to gain access to a desired card, entire echelons of cards 17 are moved pivotally about their lower edges. Likewise it is conventional to form such dividers or separators with relatively thickened frames or side edge pieces, and to provide a separator or divider between each two echelons of cards so as to prevent undue pressure of the dividers on the card echelons and thereby inhibit their displacement from normal position.

In accordance with the invention we provide main divider panels generally indicated as 9, comprising a generally rectangular side rail member 20, which may be composed of metal, wood or plastics, a pair of side rails 20 supporting between them a panel 21 composed of suitable material such as plywood, densified fiber board or the like, the panel piece 21 being preferably provided with suitable apertures 22 for relief of entrapped air in operative use. Conversely the rails 20 are preferably provided with longitudinal grooves 23 extending along each side thereof to provide cushioning air pockets between adjacent divider panels.

The side rails 20 of the main dividers terminate in a bifurcated lower end portion defined by the inner leg 24 and the outer relatively longer leg 25. The leg 24 is tapered to define a substantially knife edge parallel to the plane of panel 21, the leg 24 providing pivotal support for the divider on the base 13, and as will be noted the lower marginal edge of the panel 21 is held between the opposed end rails 20 in spaced relationship to the spacer bars 16 so that the divider panel may be freely pivoted on the base 13 and without binding engagement of the panel 21 with the bars 16.

The relatively longer legs 25 of the side rails 20 extend freely into the longitudinal channels 26 formed between the cabinet side walls 10 and the supporting base 13. In the illustrated construction, the grooves 26 are formed by flanges 27 extending laterally adjacent to the lower face of the base 13 in spaced relation to the top surface thereof, and in rabbeted engagement with the longitudinally extending mounting strips 28, the strips 28 being secured to the cabinet side walls 10 by suitable screws as indicated at 29.

The ends of the legs 25 are formed arcuate and provided with concentric frusto-conical laterally projecting bosses 30 having their axes in alignment with the knife edges of the legs 24 for cooperative engagement with angular retention pieces or shoulder strips 31 which are secured to the members 28 and extend thereon longitudinally of the cabinet.

As previously indicated the side rails 20 are formed of material such as wood, metal, or plastic and the divided or relatively thin section thereof which forms the leg 25 is resilient. Thus, when a divider panel 9 is positioned within the cabinet to extend transversely thereof, the legs 25 of the side rails 20 and their laterally projecting bosses 30 are brought into yielding abutting engagement with the longitudinal locking strips 31, and by slight downward urging movement, the legs 25 are caused to flex and to by-pass the shoulder element 31 and to be thereafter held in yield-

able locking engagement within the slots 26, with the panel 9 resting on the base 13 by means of the tapered legs 24 and being permitted to freely pivot thereon. In this manner the dividers 9 are

5 permitted to be pivotally moved and the echelons of cards spaced at their upper edges in the direction of the inclined end walls 11, and at the same time the dividers 9 are held in yieldable locked engagement sufficient to prevent their accidental 10 displacement during normal use of the filing device and to thereby prevent undue upward riding or displacement of the cards 17. The dividers 9 may be removed when desired by merely drawing them upwardly against the resistance of the resilient leg 25 and the retaining shoulder member 31.

15 As previously noted and as diagrammatically indicated in Fig. 1, two main divider panels 9 may be employed adjacent to each other with a single echelon of cards 17 between them, or one or more subdivider panels generally indicated as 32 may be employed between each pair of main divider panels 9, so that a supporting or divider surface such as that of the main panel 9 or subdivider 20 panel 32 is provided for each echelon of cards. The subdivider panel 32, similar to the main divider panel 9, is composed of an elongated sheet of fiber board 33 or the like, although the board 33 may be of relatively lighter weight than the 25 panel 32, the panel 33 being similarly provided with air relief apertures 34. The panel 33 is reinforced at its top and side edges preferably by means of a metal band 35 which extends to and terminates in the leg pieces 36 at the lower edge 30 of the panel, and panel 33 being undercut and set so that the lower edge thereof is maintained in spaced relation to the spacer bars 16 to permit free 35 pivotal movement of the panel 32 on the base 13.

The subdivider panel 32 is provided with a 40 suitable index tab 37, the tab being preferably composed of an overfolded relatively heavy strip of transparent material to provide a pocket for the reception of index data. In a similar manner the main divider panel 9, as illustrated in Fig. 5, 45 is likewise provided with index tab 38 which may be of similar construction to the tab 37 but the main divider panel 9 is additionally provided adjacent the right hand side rail 20 thereof with an additional strip of overfolded relatively heavy 50 plastic material to provide a hand hold 39 for pivotal manipulation of the main dividers, this hand hold 39 being of relatively heavier construction than the tabs 37 and 38 so as to prevent undue use of the tabs 37 and 38 and the damaging 55 thereof in turning echelons of cards and particularly groups of cards and interposed subdividers or main dividers.

In order to compensate for greater or lesser 60 number of contained card echelons in the filing device and to prevent undue slippage of the cards other than for their pivotal spacing, an end capacity adjustment member generally indicated as 40 is provided. This member 40 may be com-

65 posed of an elongated strip of sheet material 41 of wood or fiber board terminating in legs 42 which are adapted to rest on the base 13, the lower marginal edge of the panel 41 being spaced between the legs 42 from the bars 16. The panel 41 is provided with movable locking bolts 43 adjacent the upper edge thereof for locking engagement in apertures 45 provided in longitudinally extending strips 44 secured to the sides 10 of the cabinet, when the panel 41 is in an inclined position.

The locking bolts 43 are slidably mounted 70

in retaining collars 46 provided on a channel member 47 which is secured to the panel 41 by means of rivets and serves to reinforce the panel.

As will be understood, a series of locking apertures 45 are provided so that the panel end 41 may be locked in desired position depending upon the contents of the cabinet, and in an inclined position, with the panel 41 substantially parallel to the rear end wall 11.

The sides 10 of the cabinet are formed with grooves 48 to receive a roll top cover of the usual articulated construction to protect the records from damage or unauthorized use.

As shown in Fig. 1, the side rail members 20 of the several main dividers 9 are adapted to rest against each other and to be supported in an inclined plane, with the subdivider members 32 disposed therebetween. In using the file, the selected main dividers may readily be pivoted upon the knife edges formed on their inner legs 24 and it will be observed that they are maintained in proper spaced relation at their lower ends by means of the abutting arcuate ends formed on the legs 25, as illustrated in Fig. 4.

While the legs 25 have been described as being resilient to permit detachable interlocking engagement with the retaining strips 31, it is contemplated that the same detachable interlocking engagement may be obtained by forming the retaining strip 31 of resilient material for yieldably resisting movement of the frusto-conical bosses 30 into and out of engagement therewith.

We claim as our invention:

1. A record filing device of the class described comprising a cabinet having a base formed with a pair of upwardly opening channels extending longitudinally thereof adjacent the sides of the cabinet, and a separator extending transversely of said cabinet, said separator comprising a pair of side rails each bifurcated at their lower ends to define a pair of legs, one of the legs being adapted to pivotally support the separator on said cabinet base and the other of said legs being flexible in a direction transversely of the cabinet and adapted to extend freely within said channel, a locking rail, and means on said flexible leg engageable with said locking rail for retaining said separator in yieldable engagement thereby.

2. A record filing device of the class described comprising a cabinet having parallel side walls, a base and inclined end walls converging toward said base, said base being formed with a pair of upwardly opening channels extending longitudinally thereof adjacent said side walls, and a card separator extending transversely of said cabinet, said separator comprising a pair of side rails each bifurcated at their lower ends to define a pair of laterally spaced legs, one of the legs being tapered and adapted to pivotally support the separator thereby on said cabinet base and the other of said legs being relatively longer and flexible in a direction transversely of the cabinet and adapted to extend freely within said channel, locking means extending laterally of said flexible leg, and shoulder means extending longitudinally of said channel for engagement with said locking means for retaining said separator in yieldable engagement thereby.

3. A record filing device of the class described comprising a cabinet having a base formed with a pair of upwardly opening channels extending longitudinally thereof adjacent the sides of the cabinet and a record card separator extending transversely of said cabinet, said separator com-

prising a pair of side rails each bifurcated at their lower ends to define a pair of inner relatively rigid and a pair of outer relatively flexible legs, the inner legs being tapered and adapted to pivotally support the separator thereby on said cabinet base and the outer legs being relatively longer and flexible in a direction transversely of the cabinet and adapted to extend freely within said channel, a frusto-conical projection extending laterally from each of said outer legs, and retaining shoulders extending longitudinally of said cabinet and projecting over said channels for engagement with said frusto-conical projections for retaining said separator in yieldable pivotal engagement therewith.

4. A record filing device of the class described comprising a cabinet having parallel side walls, a base and inclined end walls converging toward said base, said base being formed with a pair of upwardly opening channels extending longitudinally thereof adjacent said side walls, and a card separator extending transversely of said cabinet, said separator comprising a relatively thin apertured panel substantially equal in width to that of the base between the channels and a pair of relatively thicker side rails engaged to sides of the panel, each of said side rails being bifurcated at their lower ends to define a pair of laterally spaced legs, one of the legs being tapered and adapted to pivotally support the separator thereby on said cabinet base and the other of said legs being relatively longer and flexible in a direction transversely of the cabinet and adapted to extend freely within said channel, locking means extending laterally of said flexible leg, and shoulder means extending longitudinally of said channel for engagement with said locking means for retaining said separator in yieldable engagement thereby.

5. In a record filing device having card dividers, supporting surface means for said dividers, a pair of spaced parallel locking rails extending parallel with said divider supporting surface means, said dividers having side rails, knife edges formed on the lower ends of said side rails for pivotal engagement with said divider supporting means, the lower ends of said rails also being formed with arcuate end portions laterally of and projecting below said knife edges and having the axes of said arcs in alignment therewith, and locking means provided on the arcuate end portions of said side rails for yieldably detachable locking engagement with said locking rails.

6. In a record filing device having card dividers, supporting surface means for said dividers, a pair of spaced parallel locking rails extending parallel with said divider supporting means and in spaced relation thereto providing channels therebetween, said dividers having side rails each terminating in stepped dual lower end portions, the inner of said stepped end portions being adapted to rest on said supporting surface and to retain said dividers in pivotal relationship therover, the outer of said stepped end portions projecting below the former and being adapted to extend freely into said channels and including means for yieldable locking engagement with said locking rails.

7. In a record filing device having card dividers, supporting surface means for said dividers, a pair of spaced parallel locking rails extending parallel with said divider supporting surface and in spaced relation thereto providing upwardly opening channels therebetween, said dividers having side rails each terminating in stepped dual

lower end portions, the inner of said stepped end portions being formed with knife edges for pivotally positioning the dividers on said supporting surface, the outer of said stepped ends being formed with arcuate terminal portions adapted to extend freely into said channels, and means projecting laterally from said terminal portions for yieldable engagement with said locking rails, the side rails of each divider being arranged for abutment against the side rails of adjacent dividers and of sufficient thickness to enclose cards and subdivider panels between the dividers.
